J. C. GROGAN

INCANDESCENT ELECTRIC LAMP

Filed Jan. 24, 1921

FIG. 1.

FIG. 2.

FIG. 3.

INVENTOR

JACOB C. GROGAN

BY

Merle S. Barr

ATTORNEY

UNITED STATES PATENT OFFICE

JACOB C. GROGAN, OF NEWARK, NEW JERSEY, ASSIGNOR TO WESTINGHOUSE LAMP COMPANY, A CORPORATION OF PENNSYLVANIA.

INCANDESCENT ELECTRIC LAMP.

Application filed January 24, 1921. Serial No. 439,372.

To all whom it may concern:

Be it known that I, JACOB C. GROGAN, a citizen of the United States, and a resident of Newark, in the county of Essex and State of New Jersey, have invented a new and useful Improvement in Incandescent Electric Lamps, of which the following is a specification.

My invention relates to improvements in incandescent lamps, particularly of the miniature type.

Miniature lamps heretofore manufactured for use in the dental and medical professions have not met requirements, chiefly because they have given scattered light of non-uniform intensity. It is an object of this invention to meet such requirements by providing a lamp which will project a sharply defined circular spot of light of uniform intensity.

In the accompanying drawing Fig. 1 is a plan or top view of my lamp; Fig. 2 is a side view; and Fig. 3 is an enlarged view, partly in section.

Like numerals indicate like parts in the several views.

My lamp includes the usual base 2 having a bulb 3 cemented thereto in the usual manner. The bulb, as illustrated, is substantially of frusto-conical shape, and the larger end thereof is provided with a lens 4, formed as an integral part of the bulb.

The bulb 3 is composed of two layers of glass, as is usual in lamps of this class, being formed by fusing a tube of so-called opal glass within and to a tube of clear glass. The clear or transparent tube is of such greater length than the opal tube that, when in a plastic state, it may be molded to close the end of the tube and to form a lens thereon.

In practicing my invention, I form the bulb of frusto-conical shape, the side walls of which are rendered opaque or translucent by the layer 5 which is combined with, or fused to, layer 6. My lamp, therefore, differs from previous lamps partly in having side walls so formed and disposed as to provide a reflecting surface having such re-

lation to the luminous source that the reflected rays will be directed through the lens 4 and thereby generally improving the optical system. The smaller end of the bulb is secured to the screw plug or base 2. A filament 7 is mounted upon supports 8 which are held in fixed relation by means of a bead 9 which is fused thereabout.

The peculiar shape of the bulb provides a reflecting surface whereby the reflected rays are directed through the lens. The bead 9 is composed of a material which also reflects light whereby the effective reflecting area within the bulb is somewhat increased.

It has been found, in practice, that the strength of the bulb is greater if a ring or annulus 10 of clear glass is provided intermediate the lens and the opaque portion of the bulb.

The small size of my lamp and the fact that it produces a sharply defined circular spot of light of uniform intensity make it especially applicable to a variety of uses.

What I claim is:

1. An incandescent electric lamp adapted for the projection of a concentrated beam of light, comprising a frusto-conical body having an inner light reflecting layer and an outer transparent layer fused thereto, a concentrated light source disposed within said body, a base at the lower end of the body, a cover for the upper end of said body comprising a continuation of the said transparent layer and a lens integral with said cover.

2. An incandescent electric lamp adapted for the projection of a concentrated beam of light comprising a frusto-conical body having a light source mounted on support members within said body, a bead of light reflecting material connecting said support members, a layer of light reflecting material upon the surface of said body, a base at the smaller end of said body, a cover for the upper end thereof and a lens integral with said cover.

3. An incandescent electric lamp adapted for the projection of a concentrated beam of light comprising a frusto-conical body

having a light reflecting inner layer and an outer transparent layer fused thereto, a concentrated light source disposed within said body and carried on support members, 5 a bead of light reflecting material connecting said supporting members, a base at the smaller end of said body and a cover for the

larger end of said body comprising a continuation of one of said layers and a lens integral with said cover.

In testimony whereof, I have hereunto subscribed my name this 22nd day of January, 1921.

JACOB C. GROGAN.
